UNITED STATES PATENT OFFICE.

ANDREW ELWORTHY ADAMS, WILLIAM ALFRED SHEFFIELD, AND JOHN HALLAM, OF LEICESTER, ENGLAND.

APPARATUS FOR PRODUCING ORNAMENTAL CIRCULAR-KNITTED FABRICS.

SPECIFICATION forming part of Letters Patent No. 557,631, dated April 7, 1896.

Application filed September 24, 1894. Serial No. 523,993. (No model.) Patented in England March 10, 1893, No. 5,190.

To all whom it may concern.

Be it known that we, ANDREW ELWORTHY ADAMS, WILLIAM ALFRED SHEFFIELD, and JOHN HALLAM, subjects of Her Britannic Majesty Queen Victoria, residing and carrying on our business at Adelaide buildings, Albion Street, Leicester, in the county of Leicester, England, have invented new and useful Improvements in Apparatus for Producing Ornamental Circular - Knitted Fabrics, (for which we have obtained a patent in Great Britain, No. 5,190, bearing date March 10, 1893,) of which the following is a specification.

This invention relates to improvements in apparatus for producing ornamental circular-knitted fabrics—that is to say, to produce upon circular-knitting machines “ribbed stripes,” fancy plaids, checks, diamonds, mottled stripes, and patterns of different angles—without tucking or throwing any loose threads in any part of the work, at the same time producing a solid-knitted fabric.

The principal object of this invention consists in the means of producing the fancy fabrics above mentioned upon a “swing-jack” machine and the employment of some of the mechanism shown and described in our British Patent No. 19,534 of 1889, and hereinafter described, the apparatus, as a whole, being applicable to any circular knitter or circular-knitting machine by making slight alterations. We attain these objects by the mechanism illustrated in the accompanying drawings, in which are shown the appliances and various-patterned ribbed fabrics and articles produced thereby in accordance with this invention.

Figure 1 shows, partly in section, an elevation of a two-feeder swing-jack knitting-machine with our apparatus attached thereto, the two sets of needles employed carrying different-colored yarns, and when the frame-needles are not knitting the machine-needles intercept and take up the knitting. In consequence of this, and that the needles never take two threads, no loose loops are formed on either side or face of the fabric. Fig. 2 represents the bottom ring or bed of the aforementioned machine and upper view of the “jacquard” and our apparatus for carrying out

this invention. Fig. 3 illustrates in diagram a piece of circular-ribbed knitted web or fabric of a “square” or “check” pattern with a mottled ground. Fig. 4 shows a piece of circular web having vertical stripes on a mottled ground, the dotted lines indicating that ordinary fingers and thumb can be attached thereto, and so form gloves. Fig. 5 is another piece of circular web consisting of a “one-colored” portion to form, say, the top of a sock or the cuff or gauntlet, and a “mottled” portion striped with another colored thread to make a glove-hand or leg portion of a sock or the like, the dotted line showing that the leg portion may be extended and heeled and footed in any well-known manner. Fig. 6 represents an article of tubular hosiery, such as a ribbed shirt, vest, bodice, or other like “underwear,” or guernsey, football-jersey, or other ribbed goods of a similar kind, being articles of overwear; and Figs. 7, 8, and 9 show the various cylinder-jacks employed and arranged in the cylinder in any defined manner according to the pattern desired, an example of which is hereinafter explained.

Similar letters of reference indicate like parts in all the drawings.

To carry out our invention, we secure to the bed or bottom ring of the machine a bracket A carrying the rack or cam-wheel N, Figs. 1 and 2, and the jacquard or combing apparatus in connection therewith. In conjunction with these appliances we employ a small rack or check wheel c, having upon its under side two rows of cams or inclines D D', which vary in length according to the width of the pattern it is desired to produce, the wheel C being racked by the lever E arranged at the lower end of the vertical spindle e carried in the bracket A. A roller e' is carried in the outer end of said lever E, engaging with the ordinary revolving cam e² of the machine. A lever F is attached to the spindle e, to which is linked the pawl G held to the teeth of the wheel C by spring C'.

By racking the cam-wheel C the cams D D' come in contact with and depress the foot H of the rocking lever W and the foot H' of the lever W', and operate the cams w⁴ and w⁵, respectively. The said cams are vertically-sliding cams which regulate the feet and tails

of, and the longitudinal movement of, the cylinder-needles in carrying out our invention, in the following manner and according to the following description.

5 For a spot or stripe such as J, Fig. 4, or to cause a break in a check K either at the corners or center of the pattern, as may be required and as the jacquard shall determine, the long-tailed jacks I', Fig. 8, are used, or 10 they may be steel-wire needles of a similar form and having a shunted foot i' and extended tail i², so that they can by this means be brought either into the full or half-way position and independently of the jacks I, Fig. 7, (which are of the ordinary kind,) by 15 the cam w⁵, under the control of lever W', acting upon the cam D' in the wheel c. The cam w⁴ operates the jacks I², while the jacks I will be always knitting. Such jacks I² have 20 their feet shunted i', Fig. 9, and are arranged in the nicks of the needle-cylinder in such a predetermined manner that they can be operated at any desired point in any course or courses of knitting to produce a square or 25 check pattern in a ribbed mottled fabric to be made up into body-garments, as L, Figs. 3 and 6. The jacks are set in the needle-cylinder according to the size and width of the square or the "stripe" desired. For example, we take two jacks each of I, I', and I² 30 and arrange them successively in the needle-cylinder, and use two feeders of different colored yarns. This would produce a check pattern of four needles wide, when by lowering 35 the cam w⁵ the width of the pattern would be increased to six needles of the color desired and regulated by each feeder.

To produce vertical stripes, the five wales (or more or less) forming the stripe—say 40 "black"—l' and the jacks I² are lowered below the knitting-race M (by depressing the cam w⁴) at the time that they are passing the feeder carrying a different-colored thread l², which thread is not taken up by the vertical 45 needles; but at the next feeder carrying the black thread, then both the machine and frame needles come into the knitting position in as many revolutions or courses as may have been previously determined upon. The 50 shunted-footed jacks take up only the black thread, while the ordinary-footed frame, as well as the machine-jacks, will take up and be knitting the other-colored thread or threads employed, and it will be understood that the 55 needles only take up one thread at a time. Now, to break such vertical stripe into squares or checks, Figs. 3 and 6, the cam D on the checking-wheel C depresses the tail of the lever W and raises the cam w⁴, so bringing 60 the jacks I into the same knitting position as

the ordinary jacks I, thereby crossing the stripe with a mottled course or courses, such patterns having no loose loops occurring on the inside of the fabric. The machine-needles always make two loops to the frame-needles' 65 one, and when plain fabrics are desired of course loose loops will occur in the fabric. To carry such arrangements out automatically, the "dogs" used are set at intervals in the links of a pattern-chain, according to the size 70 of pattern it is desired to make. Such apparatus is operated upon from and by the revolution of the machine in the following manner: The rack-wheel C is controlled by the pivoted lever n, the outer end of which 75 is bent or hooked to catch against the hook end of the pawl G, Fig. 1, to hold said pawl from racking the wheel C when the machine is only required to knit the top and welt O of the sections or pieces of web to form or 80 which are afterward cut in lengths and formed into such articles, as exemplified in the drawings which accompany this specification. The inner end of the controlling-lever n engages with the inner ring n' of the cam-wheel N and 85 is held thereto by the spring n². The racking of such cam-wheel N is accomplished by the pawl and levers and apparatus shown in Fig. 2 or others of a well-known or similar character. When the inner end of controlling- 90 lever w falls into a recess off the cams in the cam-ring N, the outer end of such lever releases its hold of the pawl G and allows it to rack the wheel C and so cause, as before stated, the shifting of the needles to make 95 the desired ornamental pattern fabric.

Having now explained the working of such apparatus and ascertained the nature of this invention and in what manner the same is to be performed, what we desire to secure by 100 Letters Patent and claim is—

The combination in a knitting-machine of a bracket, a rack, cam-wheel N carried in said bracket; a Jacquard or patterning mechanism in connection therewith, a check-wheel Chav- 105 ing on its under side cams D, D' varying in length; a lever E on vertical spindle e, lever F, pawl G, spring C' (for holding and racking check-wheel C), roller e', engaging cam e² of the machine in operation and in conjunction 110 with the pivoted lever n; rocking lever W, cams w⁴, w⁵, and jacks I' and I², all for the purpose substantially as described.

ANDREW ELWORTHY ADAMS.
WILLIAM ALFRED SHEFFIELD.
JOHN HALLAM.
